UNITED STATES PATENT OFFICE.

EARL G. WATROUS, OF CHICAGO, ILLINOIS.

FLUSHING APPARATUS FOR WATER-CLOSETS.

Specification of Letters Patent.

Patented Mar. 21, 1916.

1,176,114.

Application filed August 13, 1912. Serial No. 714,805.

To all whom it may concern:

Be it known that I, EARL G. WATROUS, a citizen of the United States, residing at Chicago, in the county of Cook and State of Illinois, have invented certain new and useful Improvements in Flushing Apparatus for Water-Closets, of which the following is a description, reference being had to the accompanying drawings, forming part of this specification.

My invention relates more particularly to water closets of the class in which the flushing apparatus of the closet is operated or controlled by the seat of the closet, and has for its object certain improvements in such apparatus and in its operation by the closet seat, whereby the degree of movement of the seat required for the operation of the apparatus, and the wear and tear and strain upon the operating connections, are both greatly reduced, and whereby the efficiency of the flushing apparatus is at the same time increased. Its novelty will be hereinafter set forth and particularly pointed out in my claims.

In the accompanying drawings Figure 1 is a middle section of my improved flushing apparatus and of the upper rear portion of a water closet to which it is shown applied, with the parts in their normal position of rest, and Fig. 2 a corresponding view with the parts in the position which they occupy when the closet seat is depressed.

The same reference letters are employed to indicate corresponding parts in both views.

My improved flushing apparatus embodies a valve mechanism inclosed within a casing comprising a vertical rear portion A of a general cylindrical form and an integral forwardly extending delivery pipe B which extends through and is supported in the spud connection C of the closet and has its reduced forward end D projecting through and opening provided for it in the front wall E of the inlet chamber F of the closet, said pipe B thus serving to connect the valve casing to and support it upon the closet. The pipe B is provided within the inlet chamber F with ports G for the delivery of water into said chamber, whence it may pass by the usual side ducts formed in the closet to the jet at the bottom of the bowl, while the extreme forward end of the pipe opens into the flushing rim H of the bowl and delivers into the latter a portion

of the water admitted to the pipe, the remainder escaping through the ports G, into the inlet chamber F.

The rear vertical portion A of the valve casing has its lower portion formed into a cylinder I whose open lower end is closed by a screw cap J and within which works a piston K carried by the lower end of a vertical stem L whose extreme upper end carries the main valve M which is located within the inlet chamber N of the valve casing and seats upon the bottom wall thereof. The inlet chamber N is provided (upon one side) with a pipe connection O for the water supply, such connection being shown in dotted lines upon the farther side of the chamber in Figs. 1 and 2, and its open upper end is closed by a screw cap P which also serves in the present instance to confine within the chamber a coiled spring Q which bears at its lower end upon the valve M and serves to yieldingly hold the latter to its seat.

The cylindrical portion I of the casing, in which the piston K works, terminates at its upper end in a slightly enlarged chamber R whose upper wall is formed of a horizontal diaphragm or partition provided with a large central opening the lower surface of whose surrounding wall constitutes a valve seat S for a second valve or closure T carried by the same stem L as the piston K and valve M, such valve T having a tapered or conical hub U for a purpose hereinafter explained. The chamber V, above valve seat S and beneath the inlet chamber N, communicates through the pipe connection W with a pipe X leading to a closed tank Y, said pipe and tank being diagrammatically indicated in reduced size in the drawings.

The inlet chamber N at the top of the valve casing communicates at its lower end by a duct Z with a valve chamber A¹ containing a valve B¹ carried by the lower end of a valve stem C¹ extending upward through the casing and connected at its upper end to the rear end of a lever D¹ rigidly secured at its forward end to the closet seat E¹ and having the axis F¹ of the hinges thereof for its fulcrum. The duct Z leading from the inlet chamber N to the valve chamber A¹ opens upwardly through the bottom of the latter at its center and has a seat formed around it for the valve B¹, while at one side of the duct Z there also

opens into the bottom valve chamber A¹ the upper end of a duct G¹ leading diagonally downward and rearward and opening into the lower portion of the cylinder I in 5 which the piston K works. Where this duct G¹ crosses the delivery pipe B it is inclosed within a tube extending across the interior of said pipe, leaving the water free to flow from the chamber R within the valve casing 10 around said tube and through the pipe B. To compensate for the obstruction to the flow of water offered by such tube the sides of the valve casing and of the pipe B are laterally enlarged opposite the said tube, 15 as shown at H¹.

Under the construction so far described, water under pressure is constantly admitted to the inlet chamber N of the casing and thence through the duct Z to the under side 20 of the valve B¹, which latter is held to its seat by a coiled spring I² surrounding the valve stem C¹ and exerting a downward pressure upon the valve. When the closet seat is depressed and the valve B¹ thereby 25 slightly lifted as in Fig. 2 water under pressure will pass from the duct Z to the upper end of the duct G¹ and thence through the latter to the under side of the piston K, which latter is of such large area that it 30 will be quickly lifted by the pressure beneath it against the resistance of the spring Q (when the latter is employed) and the water pressure upon the upper side of the valve M within the inlet chamber N. The 35 upward movement of the piston K and parts carried by or moving with it will be limited by the contact of the valve T with the valve seat S, in which position the valve T will serve to cut off communication between the 40 chambers V and R above and below said valve. In this position of the parts, as shown in Fig. 2, a cut-away or winged portion J¹ of the valve stem L will extend through the valve seat on which the valve M 45 normally rests, so that water under pressure may freely pass from the inlet chamber N to the chamber V beneath it, and thence through the pipe connection W and pipe X to the closed tank Y. Said tank thus becomes 50 filled or partially filled with water under pressure while the parts are held in the position shown in Fig. 2 by the depression of the closet seat. Upon the release of the latter the spring I¹ will reseat the valve B¹ and thereby cut off the admission of water under pressure through the ducts Z and G¹ to the under side of the piston K. The pressure of the water upon the upper 55 side of the valve T (supplemented by the pressure of the spring Q when the latter is employed) tends to force the piston downward and unseat and open the valve T and close the valve M, and to permit it to do so, upon the release of the closet seat and the reseating of the valve B¹, the following pro-

vision is made for the escape of water from the under side of the piston, through the duct G¹ and valve chamber A¹. The upper end of the valve chamber A¹ is closed by a flexible washer K¹ upon which rests a 70 metal washer L¹, the two being held in place by the lower end of a screw cap M¹ whose interior forms a chamber N¹ for the reception and confinement of the coiled spring I¹ heretofore referred to. The lower end of this spring bears upon a disk or collar O¹ which in turn rests upon the upper end of the hub of the valve B¹, which hub extends through central openings in the washers K¹ L¹ of slightly larger diameter 80 than that of the hub itself, thus providing a reduced passage-way, around said hub, between the valve chamber A¹ and the chamber N¹ above it when the valve B¹ is in lower position against its seat. When the 85 valve B¹ is lifted, as heretofore described, at the depression of the closet seat, its upper surface will seat against the under surface of the washer K¹ and close this passage around the hub of the valve, so that during 90 the time the closet seat is depressed no water can escape from the valve chamber B¹ through such passage; but when the valve B¹ is forced downward against its seat, at the release of the closet seat, said 95 passage will be opened, and thereby afford an escape for the water beneath the piston K through the duct G¹ and valve chamber A¹ into the chamber N¹. The latter chamber is provided in its lower end with lateral 100 ports P¹ (formed of notches in the lower edge of the circular wall of the screw-cap M¹) which communicate with a chamber Q¹ into which opens the upper end of a duct R¹ whose lower end opens into the delivery 105 pipe B. The upper end of the duct R¹ is controlled by a regulating screw S¹, by means of which the escape of water from beneath the piston K may be regulated as desired, and the speed of the closing movement of the valve M and opening movement of the valve T be thereby controlled. The opening of the valve T places the closed tank Y in communication, through the pipe 110 X and chambers V and R, with the delivery 115 pipe B, so that the water which has been admitted to said tank during the depression of the closet seat will, upon the release of the latter, be discharged through the pipe B into the closet to flush the same, the greater 120 portion of said water passing through the ports G G into the inlet chamber F of the closet and thence through the usual side ducts to the jet at the bottom of closet bowl, and the remainder passing through the extreme 125 front end of the pipe B into the flushing rim of the closet, to supply the necessary rim flush. The valve T is provided with the conical or tapered hub U in order that as said valve is lowered away from the seat S 130

the opening through said seat will be gradually enlarged, and thus afford increasingly free passage for the water through said seat as the pressure of said water decreases, thereby producing a uniform flushing of the closet. At the opening of the valve T and closing movement of the valve M the passage of the water from the inlet chamber N to the chamber V beneath it will be cut off as soon as the winged portion J¹ of the valve stem L passes through the opening in the bottom of the chamber N and the solid and cylindrical portion of the stem L enters said opening, with the result that at such time the pressure of the water within the chamber N, exerted upon the top of the valve M, will supplement the pressure of the water upon the top of the valve T, in forcing the parts downward and fully opening the valve T and closing the valve M.

The spring Q, exerting downward pressure upon the main valve M and other parts carried by the valve stem L, merely supplements the water pressure in exerting a downward pressure upon said parts, and is not at all essential to the operation of my apparatus. The main valves M and T of the apparatus are operated primarily (and may be operated solely) by the water pressure, and have no mechanical connection whatever with the closet seat, so that the sole work which the closet seat and its connections are called upon to perform, in operating the apparatus, is to lift the valve T a very small fraction of an inch (a sixteenth or even a thirty-secondth of an inch will suffice) against the resistance of the coiled spring I¹. The closet seat and its connections are thus not only required to do very much less work, and are subjected to much less wear and tear and strain, than where the main valves of the flushing apparatus are operated by a direct mechanical connection with the closet seat, but inasmuch as the controlling valve B¹ is required to have but a trifling amount of movement, as compared with the necessary movement of the main valves, it follows that only a small amount of movement of the closet seat is required for the operation of said controlling valve.

My improved construction of flushing apparatus, and particularly the method of connecting it to and supporting it upon the closet, also facilitates its application to closets of standard construction and obviates the necessity of any special design of closet for its employment. The spud connection C which forms the main support for my improved valve mechanism may be the ordinary connection for the supply pipe for the closet, so that the only modification that is required in the ordinary or standard construction of the closet is the forming of the hole in the front wall E of the inlet chamber F for the reception of the reduced front end

D of the delivery pipe B and this can be readily provided without any mutilation of the closet.

Having now fully described my invention, I claim:

1. In a flushing valve, the combination with the valve casing containing the inlet chamber N, outlet chamber R, intermediate chamber V and piston chamber I, of the valve M controlling communication between the chambers N and V, the valve T controlling communication between the chambers V and R, and the piston K working in the chamber I, said valves and piston being carried by the stem L, said valve having the upper half thereof solid or cylindrical adjacent the valve M and the lower half cut-away or winged beneath said solid or cylindrical portion, and means for admitting pressure to and releasing it from the chamber I beneath the piston K; substantially as described.

2. In a flushing valve, the combination with the valve casing containing the inlet chamber N, outlet chamber R, intermediate chamber V and piston chamber I, of the valve M controlling communication between the chambers N and V, the valve T controlling communication between the chambers V and R and having the tapered portion U, and the piston K working in the chamber I, said valves and piston being carried by the stem L having the upper half thereof solid or cylindrical adjacent the valve M and the lower half cut-away or winged beneath said solid or cylindrical portion, and means for admitting pressure to and releasing it from the chamber I beneath the piston K; substantially as described.

3. In a flushing valve, the combination with the valve casing having the inlet chamber N, outlet chamber R, intermediate chamber V and piston chamber I, of the inlet valve M of puppet form seating upon the upper side of the diaphragm separating the chambers N and V, the outlet valve T of puppet form seating upon the under side of the diaphragm separating the chambers V and R, and the piston K working in the chamber I, said valves and piston being carried by the stem L and moving in unison with each other, and means for admitting pressure to and releasing it from the chamber I beneath the piston K; substantially as described.

4. In a flushing valve, the combination with the valve casing containing the inlet chamber N, outlet chamber R, intermediate chamber V and piston chamber I, of the valve M controlling communication between the chambers N and V, the valve T controlling communication between the chambers V and R, the piston K for operating said valves, and means for admitting pressure to and releasing it from the chamber I.

beneath the piston K, said means comprising the supplemental valve chamber A¹ having the inlet passage Z opening upward through its bottom and having its top formed by the disks K¹ L¹, the passage G¹ connecting the chamber A¹ with the piston chamber I, the escape passage P¹ R¹ leading from the space above the disks K¹ L¹ and regulated by the screw S¹, the supplemental valve B¹ having the hub passing loosely through central openings in the

disks K¹ L¹ and operating in its lower position to close the inlet passage Z and in its upper position to seat against the disk K¹ and close the passage therethrough around the hub of the valve, and the spring I¹ for yieldingly holding the valve B¹ in its lower position; substantially as described. 15
EARL G. WATROUS.
